UNITED STATES PATENT OFFICE

WILLIAM S. MONROE, OF CHICAGO, ILLINOIS

TOWEL RACK

Application filed July 7, 1928. Serial No. 291,051.

This invention relates to towel racks and has to do particularly with a towel rack adapted for attachment to a radiator for the purpose of employing the support afforded by the radiator for holding the towels or other articles without a rack separately attached to the wall, and for the additional purpose of utilizing the heat from the radiator for drying and keeping the towel dry at all times.

I am aware that drying racks have been previously attached to radiators for the purpose of utilizing the heat from the radiator for drying articles suspended from the rack, but the racks of this sort heretofore provided have been more in the nature of clothes racks, which are not usually in constant use, but are set up for drying small washings and taken down or removed when not in use. Where the device is not ordinarily in place, but is set up from time to time, the appearance has been a secondary matter and attractiveness of the attachment when in place has had little attention. The wash itself is unsightly when in place and no manner of improving the appearance of the rack would overcome this. In addition, in the previous racks the clothes have usually been suspended over the top of the radiator in order to obtain the necessary drying effect. This overhead arrangement is not only particularly unsightly but it requires an overhead clearance above the radiator and impairs movement about the room when the rack is in place, which where the rack is set up infrequently and only for short periods of time has been tolerated. It is now common to provide a cover or shield over the top of the radiator which will interfere with access to the tops of the radiator coils for the purpose of attaching an overhead rack thereto.

The object of my present invention is the provision of a generally improved and simplified rack of pleasing appearance which is used in much the manner of the fixed rod towel racks, now usually attached to the wall as distinguished from a cumbersome clothes rack which is set up and taken down from time to time. The present rack is in constant position for use, although the attachment

provided therefore is preferably detachable so that the rack may be conveniently applied and removed as, for example, upon the termination of the tenancy of the premises. The rack is preferably so attached that it holds the towel or other article in front of the radiator and preferably below the top of the radiator to avoid interference with a cover or shield therefor, although this may vary. The device is primarily a towel support so that the overhead drying effect is not necessary yet, at the same time, if the towel or other article is damp or wet the heat from the radiator will dry it. The disposition of the towel or other article in front of the radiator and preferably parallel thereto makes for compactness and avoids impairment to movement about the room. In addition this disposition in front of the radiator has the further and important function of forming a protector or shield for preventing accidental direct contact with a hot radiator coil. The support upon the radiator eliminates the necessity of separate or additional supports or wall brackets, as well as any possibility of marring the wall by setting up and taking down such brackets, and the present device may be applied without becoming a part of the premises.

The invention is illustrated in the accompanying drawings, in which:

Fig. 1 is a fragmentary perspective view of a radiator showing a rack embodying the present invention applied thereto;

Fig. 2 is a front elevation of the attachment and rod supporting fitting at one end of the rack;

Fig. 3 is an outer side elevation of the attachment and rod supporting fitting shown in Fig. 2; and

Fig. 4 is a horizontal section taken on the line 4—4 of Fig. 3.

Referring to the drawings, I have shown more or less illustratively at 5 a radiator to which the present invention is adapted to be applied. The radiator may be a steam, hot water or other radiator and it may be of existing or preferred form usually comprising a plurality of spaced, upright or vertical sections or coils 6, as well understood.

The rack comprises a rod or supporting member 10 and a duplicate pair of attachment and rod supporting brackets or fittings 12, 12, one at each of the opposite ends of the 5 rod or supporting member 10. Each fitting 12 comprises an outwardly extending arm 13 preferably of channel formation, as shown for strength. At the inner end of the arm 12 is a base 14 which is preferably integral with the 10 arm 13 and preferably in the form of a closed end for the channel formation of the arm, although this may be varied. The base 14 is apertured at 15 and its inner surface is formed at 16 to fit between and engage the walls of 15 two adjacent coils or sections 6 of the radiator 5.

At its outer end the arm 13 is provided with a head 18 which is preferably formed integral with the arm 13. The upper and 20 lower generally horizontal flanges of the channel arm 13 preferably converge at 20 toward the head 18. The head 18 is in the form of a generally spherical hollow shell provided with an opening 21 for receiving 25 and supporting one end of the towel supporting member 10, which member is preferably in the form of a rod circular in cross section and telescoping at one end through the opening 21 and into the hollow head 18 of one of 30 the arms or brackets 12 and similarly engaged at its opposite end in the corresponding head of the other arm or bracket 12.

Each arm 13 has an associated clamping member 25. The clamping members 25 are 35 formed similar to the bases 14 of the arms 13 and engage between and at 26 with the walls of adjacent coils or sections 6 of the radiator 5. Each clamping member 25 has an aperture 28 which registers with the aperture 15 in 40 the base 14 of the associated arm 13 and a suitable bolt 30 is passed through the registering apertures 15 and 28 and is engaged in a nut 32 which is drawn up to draw the base 14 and clamping member 25 into firm holding engagement with the radiator sections to clamp 45 the supporting bracket or arm firmly thereto.

From the foregoing it will now be apparent that the arms 13, 13 extend substantially horizontally from the front of the radiator 55 and support the rod 10 in front of the radiator and substantially parallel therewith. This makes for compactness and there are no overhead obstructions to impair movement about the room or render the radiator unsightly. The towels or other articles may be supported upon the rod 10 by folding them thereover in the usual manner and are thereby supported in front of the radiator and generally parallel therewith. The extension 60 from the front of the radiator need not be great, which makes for further compactness and the disposition of the towels or other articles in front of the radiator in this manner, has the important function of forming 65 a protector or shield for preventing burning

or injury to the occupants of the room by accidental direct contact with the front of a hot radiator coil or section. The device is adapted to be positioned constantly in front of the radiator and to serve as a towel rack, as distinguished from cumbersome extending clothes racks which are set up for use and removed when not in use. At the same time if the towel or other article is damp or wet the heat from the radiator will dry it. The 70 brackets or fittings 12, 12, together with the clamping members 25 and bolts 30 may be nickelized or finished, as desired, and the rod 10 may also be finished as desired, and while 75 preferably of metal may be of any suitable or preferred material. The device may be removed simply by removing the nuts 32 and the clamping attachment disclosed is obviously adjustable to radiator sections of different sizes and different contour simply 80 by threading the nuts 32 outwardly or inwardly upon the bolts 30. With the arrangement described the opposite ends of the rod 20 are inserted into the headed ends 18 of the arms 13 before both arms 85 90 are attached to the radiator and the attachment of these arms to the radiator is then completed. Obviously, one of the headed ends 18 of one of the arms 13 may be formed to receive the adjacent end of the rod 10 after 95 both arms or brackets are attached to the radiator and such a departure from the disclosed structure is contemplated within the spirit and scope of the present invention.

I claim:—

1. In a towel bar fixture for attachment to a radiator, the combination of a pair of one-piece brackets each having a clamping base at one end adapted to fit between the coils of a radiator with an integral hollow head at the 105 opposite end of each bracket, said heads each having a lateral opening in one side of the wall thereof, a securing means passing through each of said bases, said heads each being offset to permit of accessibility to said 110 securing means, a bar disposed across the front of the radiator with its respective ends extending through said openings and supported directly in the walls of said hollow bracket heads, the respective ends of said bar 115 cooperating directly with the walls of the hollow bracket heads opposite the lateral openings of each and held against endwise displacement thereby, and means cooperating 120 with said securing means for attaching the brackets to the radiator coils.

2. In a towel bar fixture for attachment to a radiator, the combination of a pair of one-piece brackets each having a clamping base at one end adapted to fit between the coils of a radiator with an integral hollow head at the opposite end of each bracket, said heads each having a lateral opening in one side of the wall thereof, a securing means passing through each of said bases, said heads each 125 130

being offset to permit of accessibility to said securing means, a bar disposed across the front of the radiator with its respective ends extending through said openings and supported directly in the walls of said hollow bracket heads, the respective ends of said bar cooperating directly with the walls of the hollow bracket heads opposite the lateral openings of each and held against endwise dis-
5 placement thereby, and means cooperating with said securing means for attaching the brackets to the radiator coils, said integral hollow bracket heads being relatively small with respect to the diameter of said bar to
10 minimize the extensions of the ends of the bar internally through said heads from one side of each head to the other.
15

In witness whereof, I hereunto subscribe my name this 29th day of June, 1928.

20 WILLIAM S. MONROE.
